D56,730 S * 12/1920 Teall D7/631

FIG. 1 is a front, top and left-side perspective view of a dispenser embodying our new design;

FIG. 2 is a rear elevational view of the dispenser of FIG. 1;

FIG. 3 is a top plan view of the dispenser of FIG. 1;

FIG. 4 is a front elevational view of the dispenser of FIG. 1;

FIG. 5 is a bottom plan view of the dispenser of FIG. 1;

FIG. 6 is an elevational view seen from the left side of the

dispenser of FIG. 1; and,

FIG. 7 is an elevational view seen from the right side of the

dispenser of FIG. 1.

In all embodiments, the material shown in broken lines signifies an absorbent sheet protruding through a top opening in the dispenser, the appearance of which sheet is not claimed.
